UNITED STATES PATENT OFFICE.

JAMES M. MONTGOMERY, OF NEW YORK, N. Y.

DESIGN FOR A PUZZLE-BOARD.

SPECIFICATION forming part of Design No. 31,723, dated October 24, 1899.

Application filed August 29, 1899. Serial No. 728,917. Term of patent 7 years.

To all whom it may concern:

Be it known that I, JAMES M. MONTGOMERY, of the city of New York, borough of Manhattan, in the county and State of New York, have 5 invented and produced a new and original Design for a Puzzle-Board, of which the following is a specification.

The leading feature of my design consists of a puzzle-board made of oblong rectangular 10 shape and in the semblance of a flag by the arrangement of parallel stripes or channels alternating with ridges and a starred corner portion separated by ridges from the portion containing the stripes.

15 The design is illustrated in the accompanying drawings, in which—

Figure 1 is a plan of a puzzle, illustrating my design; and Fig. 2 is a sectional elevation on line 2 2 of Fig. 1.

20 The puzzle-board is of oblong rectangular shape, corresponding to the shape of a flag,

and has parallel longitudinal stripes or channels *a*, separated by ridges *b*, having through-apertures *b'*, irregularly arranged. At the bottom the stripes and ridges extend the full 25 length of the rectangular figure; but at the top they stop short of the left-hand edge, leaving a rectangle *c*, which is separated from the other portion of the puzzle by one of the ridges *b* and by a transverse ridge *d*, having a 30 through-aperture *d'*. Within the rectangle *c* appear stars *e* and pins *f* and in the center a raised cylindrical body *g*, exhibiting, as at *h*, the representation of an anchor.

35

I claim—

The design for a puzzle-board, as herein shown and described.

JAMES M. MONTGOMERY.
